ROTATABLE CANISTER UNIT

Peter M. Berend, Wooster, Ohio, assignor to Rubbermaid Incorporated, Wooster, Ohio, a corporation of Ohio

Filed Dec. 23, 1966, Ser. No. 5,170

Term of patent 14 years

(Cl. D44—6)

FIG. 1

FIG. 2

Des. 209,848

PAGE 2

FIG. 3

FIG. 4

FIG. 5

FIG. 6

FIG. 1 is a top plan view of a rotatable canister unit embodying my new design;

FIG. 2 is an elevational view taken from the bottom of FIG. 1;

FIG. 3 is an elevational view when rotated approximately 140° from the position of FIG. 2;

FIG. 4 is an elevational view when rotated approximately 105° from the position of FIG. 3;

FIG. 5 is a sectional view on line 5—5 of FIG. 1; and

FIG. 6 is a sectional view on line 6—6 of FIG. 2.

I claim:

The ornamental design for a rotatable canister unit, as shown.
